UNITED STATES PATENT OFFICE.

JOHN NICHOLAS DERSCHUG, OF SYRACUSE, NEW YORK, ASSIGNEE TO SYRACUSE WASHING MACHINE CORPORATION, OF SYRACUSE, NEW YORK, A CORPORATION OF NEW YORK.

CLOTHES-WASHING MACHINE.

Application filed January 31, 1920. Serial No. 355,515.

To all whom it may concern:

Be it known that JOHN N. DERSCHUG, of Syracuse, in the county of Onondaga, in the State of New York, has invented new and 5 useful Improvements in Clothes-Washing Machines, of which the following, taken in connection with the accompanying drawings, is a full, clear, and exact description.

This invention relates to certain improvements in clothes washing machines involving the use of a suitable vat adapted to contain the washing fluid and articles to be washed, cup-shaped dashers mounted upon a vertical reciprocatory plunger, which 15 is movable through a central opening in the bottom of the vat, a wringer for feeding the clothes into and out of the vat, a motor mounted upon the supporting frame for the vat, and mechanisms for transmitting motion from said motor to the reciprocatory plunger and to the wringer, the entire combination constituting a unitary machine.

The main object of my present invention is to increase the general working efficiency 25 of the various parts of a washing machine of this type by providing the vat with a perforated false bottom a sufficient distance above the bottom of the vat to form an intervening chamber to permit the washing fluid and air to be forced by suction and pressure 30 entirely through the clothes from the bottom upward and from the top downward during the operation of the inverted cup-shaped dashers, and to thereby produce a 35 more effective and expeditious cleansing of the clothes and at the same time greatly increasing the output without adding materially to the expense of the entire apparatus.

Second, to establish a more direct drive 40 between the motor and dasher operating mechanism and also between the motor and wringer operating mechanism.

Third, to surround the guide post for the plunger by a rotary sleeve which may be 45 rotated by the clothes if they become wound around the same by the intermittent rotary motion of the dashers thereby reducing to a minimum the liability of mutilation of the clothes during the washing operation.

Fourth, to construct the yoke which connects the dashers to the plunger in such

manner that it will better resist the strain to which it is subjected without liability of bending or springing and to thereby produce a more effective pressure upon the 55 clothes during the compression stroke of the dashers.

Fifth, by yieldingly supporting the dashers upon the yoke in such manner that the connections are substantially concealed and 60 at the same time to enable the dashers to be easily and quickly removed from the yoke when desired.

Sixth, to enable the yoke to be easily and quickly adjusted vertically upon the plunger 65 and automatically locked in its adjusted position.

Seventh, to provide the vat with transparent top and side walls which effectively prevent the escape of the washing fluid 70 from the vat and also permits inspection of the washing operation.

Eighth, to support the wringer near one of the legs of the tripod in such manner that it may be swung to different positions over 75 and away from the top of the vat without liability of over-turning the machine, thereby avoiding the use of extra means of support for this purpose.

Ninth, to assemble the various mechanisms upon the machine in such manner as 80 to avoid excessive vibration thereof when in operation.

Tenth, to support the vat on the frame in such manner that it may be readily removed 85 without disturbing any of the other mechanisms except the removal of the yoke with the dashers thereon and the post.

Other objects and uses relating to other specific parts of the machine will be brought 90 out in the following description.

In the drawings:

Fig. 1 is a top plan of a clothes washing machine embodying the various features of 95 my invention.

Fig. 2 is a transverse vertical sectional view of the same machine taken on line 2-2, Fig. 1.

Fig. 3 is a top plan of the mechanism underlying the vat, a portion of the supporting 100 bed therefor being broken away.

Fig. 4 is an enlarged vertical sectional

view taken on line 4-4, Fig. 3, showing means for transmitting motion from the motor shaft to the horizontal countershaft from which power is transmitted to the dashers and to the wringer.

Fig. 5 is an enlarged sectional view taken on line 5-5, Fig. 3.

Figs. 6 and 7 are enlarged vertical sectional views taken respectively on lines 6-6 and 7-7, Fig. 1.

Fig. 8 is an enlarged horizontal sectional view taken on line 8-8, Fig. 2.

Fig. 9 is a horizontal sectional view taken in the plane of line 9-9, Fig. 7.

Fig. 10 is an enlarged vertical sectional view partly broken away, taken on line 10-10, Fig. 2.

Figs. 11 and 12 are detailed transverse sectional views taken respectively in the plane of lines 11-11 and 12-12, Fig. 10.

Figs. 13 and 14 are enlarged sectional views taken respectively on lines 13-13 and 14-14, Fig. 2.

Figs. 15 and 16 are enlarged detailed sectional views of one of the casters and its connections with one of the legs of the vat supporting frame.

The machine, as illustrated, comprises a main supporting frame --1-- having a circular platform --2-- disposed in a substantially horizontal plane and supported by a series, of, in this instance, three upright legs --3-- in uniformly spaced relation circumferentially, said legs being extended some distance above and below the plane of the platform --2--, and are secured to said platform by bolts --4--.

A circular band or ring --5-- is secured by bolts --6-- to the inner faces of the upper ends of the legs --3-- to assist the platform --2-- in holding the legs in fixed relation to each other and to said platform, said legs being preferably made of channel irons with their channels facing inwardly for imparting additional rigidity and strength thereto.

The upper ends of the inwardly projecting ribs of the legs --3-- are recessed at --7-- to form shoulders --8-- which are engaged by the lower edges of the ring or band --5-- to further stiffen the frame against torsional strains and at the same time affording a more positive connection between the band --5-- and legs.

The lower ends of the legs are mounted upon suitable casters --9-- each of which comprises a bracket --10-- a roller supporting frame --11-- having a spindle --12-- secured thereto and journaled in a socket --13-- in the bracket --10-- and a roller --14-- journaled on the caster frame --11--. The bracket --10-- is provided in one side with a vertical groove --15-- for receiving the adjacent portion of the leg --3-- and is secured to said leg by bolts --16-- and

--17--; one of which, as --16-- is of sufficient length to enter an annular groove --18-- in the upper end of the spindle --12-- to hold the latter in operative position in the socket --13-- and at the same time allow it to turn freely in said bracket, the other bolt --17-- being screw threaded into the bracket to more firmly secure it to the leg.

The lower end of each bracket is provided with a laterally projecting shoulder --19-- at the lower end of the grooves --15-- to form an abutment for the adjacent end of the leg --3-- thereby relieving the strain upon the bolts --16-- and --17-- and transmitting it directly to the bracket and casters.

A circular vat --20-- is supported directly upon the platform --2-- within the legs --3-- and ring or band --5-- so that it may be readily removed by upward displacement and is provided with a suitable lid or cover --21-- loosely resting upon its upper edge.

The major portion of the vat is preferably made of non-corrodible sheet metal but in order that the washing operation and action of the interior mechanism may be inspected from time to time, one side of the vat is provided with a transparent panel --22-- of glass or other suitable material made to conform to the curvature of the main body and has its edges suitably held against the inner faces of the marginal edges of the opening by internal flanges --23-- which may be brazed or otherwise secured to the main body 100 of the vat around the edges of the opening in which the glass panel --22-- is inserted.

The cover or lid --21-- is also provided with a central circular panel --24-- of glass or other transparent material suitably held against the inner face of the metallic portion of the cover by flanges --25-- which are clamped to the metallic portion by bolts or screws --26--, Fig. 2.

A tubular post --27-- is secured at its lower end in registering openings --28-- to the center of the platform --2-- and the bottom of the vat --20-- and rises some distance above the bottom of said vat for receiving and guiding a vertically movable plunger --29-- hereinafter described, said post being provided near its lower end with an annular flange --30-- resting upon the upper face of the bottom of the vat and is also provided with a reduced nipple --31-- extending through the registering openings --28-- and having its lower end threaded and engaged by a nut --32-- which is tightened against the underside of the adjacent portion of the platform --2-- to firmly hold the post in operative position and at the same time permitting it to be easily and quickly removed, if it is necessary, by simply removing the nut --32--.

The upper end of the post --27-- is also

threaded externally for receiving a gland and nut —33— which fits closely upon the periphery of the plunger —29— to prevent the entrance of water from the interior of the vat into the post.

The upper end of the nut —33— is reduced in diameter to form an annular shoulder —34— for partially supporting a rotary sleeve —35— which surrounds said post and has its lower end rotatably mounted upon a reduced portion —36— near the lower end of the post or just above the flange —30—, the upper end of said sleeve being crimped or turned inwardly to form an annular flange —37— which rests upon the shoulder —34—.

The reduced upper end of the nut —33— is provided with an annular groove —38— for receiving a split ring —39— which serves to hold the sleeve —35— against upward displacement and also permits the sleeve to be easily and quickly removed by simply springing the split ring —39— out of place whereupon the sleeve may be detached by upward displacement.

A perforated sheet metal plate —40— of substantially the same diameter as that of the interior of the vat is supported in said vat a short distance above and in fixed relation to the bottom thereof by means of suitable feet or projections —41— on the lower side of the plate, which is provided with a series of perforations —42—.

This perforated plate constitutes what may be termed a false bottom having its central portion provided with an opening for receiving the post —27— and sleeve —35— and allowing the said central portion to rest upon the base of the post, which additionally holds it in spaced relation to the bottom of the vat.

The object of this perforated plate is to allow the water to pass therethrough from the bottom upward and also from the top downward, which permits the clothes which rest thereon to be more thoroughly washed by the vertical reciprocatory dashers by reason of the fact that the water is free to pass entirely through the clothes in reverse directions as produced by the suction and pressure of the dasher cups hereinafter more fully described.

The plunger —29— is preferably tubular and extends entirely through and beyond the ends of the post —27— in which it is guided in its vertical movement.

A yoke —43— is adjustably mounted upon the upper end of the plunger —29— and is held in its adjusted position by a removable locking bolt —44— which is adapted to enter in one of the series of openings —45— one above the other in the plunger some distance above the upper end of the post —27— for supporting the dashers at different heights relative to said post

or rather relative to the bottom of the vat, said locking bolt being held in its locking position by means of a spring —46— which is pivoted at —47— to the yoke some distance to one side of the plunger so that the spring —46— may be moved into and out of engagement with the adjacent end of the locking bolt —44— for permitting the insertion and removal thereof into and from the apertures —45— and similar apertures —45'— in the hub of the yoke.

This yoke is provided with opposite downwardly curved arms —48— to better resist the upward thrust strains to which the outer ends thereof carrying the dashers are subjected, particularly when said dashers are brought downwardly with considerable force on the clothes lying on the perforated plate —40—.

These arms —48— are of substantially equal length and are provided at their outer ends with tubular heads —49— open at the bottom for receiving the reduced ends or hubs —50— of a pair of dashers —51—.

These dashers —51— are preferably made in the form of inverted cups or segments of spherical shells —51'—, the central portions of which are clamped between the flanged lower end —52— of the stem —50— and a washer —53— which together with the segment —51'— and base —52— of the stem —50— are provided with central registering apertures for receiving a clamping bolt —54— which extends entirely through the stem —50— and head —49— of the yoke —43— and is provided with nuts —55— and —56— engaging respectively the lower face of the washer —53— and the upper face of the head —49— of the yoke —43—, the upper face of said head being recessed at —57— to receive the nut —56— and thereby conceal the major portion thereof.

The head —49— and stem —50— of the dasher —51— are tubular and telescope one within the other. The inner end of the opening in the stem —50— and outer end of the opening in the head —49— being reduced in diameter to form shoulders —58— and —59— respectively.

A coil spring —60— surrounds the bolt —54— within the tubular stem —50— and head —49— and has its opposite ends engaged respectively with the shoulders —58— and —59— to exert downward pressure upon the dasher —51— and also to allow said dasher to yield vertically under pressure upon the clothes when drawn downwardly by the plunger —29— thereby allowing the plunger to move through its entire stroke without liability of overstraining any of the parts.

The connections between each dasher and yoke are identical and, therefore, the description given for one serves to define the other.

Plunger reciprocating mechanism.

A collar —61— is loosely mounted upon the lower end of the plunger —29— and is held against endwise movement relative to said plunger by means of a washer —62— and a ratchet wheel —63—, the washer being secured to the lower end face of the plunger by means of a screw —64— and is engaged with the lower face of the collar —61— while the ratchet wheel —63— is secured by a pin —65— to the plunger and engages the upper end face of the collar.

This collar is provided with pendent apertured lugs —66— for receiving a pivotal pin —67— which projects beyond the outer faces of the lugs for receiving and supporting a pair of links —68—, the latter being held in place by cotter pins —69— to permit the parts to be readily detached when necessary.

These links —68— extend downwardly from the pivotal pin —67— and are connected intermediate their ends by a web —70— preferably integral therewith, the lower ends of said links being apertured to receive and support a pivotal pin —71— having cotter keys —72— to hold it against endwise displacement and permit it to be easily and quickly removed when necessary.

The pin —71— is mounted upon one end of a vertically movable rocking lever —73— having its opposite end pivoted at —74— to a bracket —75— which is secured to the under side of the platform or vat supporting bed —2— said lever having its intermediate portion connected by a pitman —76— to a crank arm —77— on one end of a rotary shaft section —78— having its axis disposed at right angles to the plane of movement of the lever —73—, as shown more clearly in Figs. 2, 3 and 5.

This shaft section —78— is loosely journaled in one end of a revoluble sleeve or tubular counter shaft —79— which is journaled in bearings —80— and —81— forming parts of separate gear cases —82— and —83— both of which are secured to the underside of the bed plate or platform —2— as shown more clearly in Fig. 5, said shaft section —78— being provided with an annular groove —84— for receiving a pair of diametrically opposite retainers —85— which are secured by screws —86— to the adjacent sides of the sleeve or counter shaft —79— and serve to hold the shaft section —78— against endwise movement relatively to said counter shaft.

The inner end of the shaft section —78— is provided with a clutch face —87— operating with a companion clutch face —88— on the adjacent end of a clutch section —89— within the sleeve —79—, the intermediate portion of said clutch section —89— being provided with a diametrical

slot —90— therethrough for receiving a key or pin —91— which is secured to the opposite walls of the sleeve —79— and serves to transmit rotary motion from said sleeve to the clutch section —89— and to allow the clutch section to be moved axially within the sleeve for engaging and disengaging its clutch face —88— with and from the companion clutch face —87— of the shaft section —78—.

A spindle —92— coaxial with the sleeve —79— is loosely journaled at one end in a bushing —93— in the outer end of the clutch section —89— and extends outwardly through a gear —94— on the outer end of said sleeve, the inner end of the spindle being provided with a head —95— interposed between the inner end of the bushing and end wall of a socket —96— in which the head is rotatable to hold the clutch section and spindle against relative endwise movement and at the same time permitting relative rotation of the clutch section and spindle.

The outer end of the spindle —92— is provided with a grooved collar —97— for engagement by a shifting arm —98— which is secured to a rock shaft —99— in the gear case —83—, one end of said rock shaft being extended through a suitable opening in the gear case and is secured to a hand lever —100— by which the shifting member —98— may be rocked in reverse directions for throwing the clutch section —89— into and out of engagement with the shaft section —78— to start and stop the reciprocation of the plunger —29— carrying the dashers —51—.

The means for transmitting motion to the counter shaft or sleeve —79— comprises an electric motor —A— having its frame suitably secured to the underside of the bed plate or platform —2— and having its motor shaft as —a— disposed horizontally at right angles to the axis of the counter shaft —79— as shown more clearly in Fig. 3, said motor shaft being preferably made in sections coupled together by a universal joint —a'— to compensate for any slight variations in the alignment of the shaft sections.

A worm —B— is secured to a motor shaft section —b— which is journaled in suitable bearings —b'— in the gear case —82— and is connected by a universal coupling —C— to a loose disc or collar —c— on the adjacent end of a coaxial motor shaft section —c'—.

The disc —c— which is loose on the shaft section —c'— is connected by a slip clutch —D— to the shaft section —c'— to prevent stalling of the motor in case the load driven by the worm —B— should be excessive, said slip clutch comprising a disc —d— secured by a pin —d'— in spaced relation to the

disc —c— to receive between said discs a fibre disc —d²—.

Additional discs —e— are loosely mounted upon the shaft section —c'— between the disc —d— and adjacent end of a coil spring —E— which surrounds the shaft section —c'— and has its outer end abutting against an adjusting screw or nut —e'— which is loose on the shaft section —c'— and is 10 screwed into the adjacent end of an enclosing sleeve —E— to adjust the tension of the spring and thereby regulate the friction between the several discs, the inner end of the sleeve —F— being rigidly secured to the 15 disc —c—.

The worm —B— meshes with a worm gear —f— which is secured by a set screw —f'— to the periphery of the sleeve or countershaft —79— between the opposite end 20 walls of the gear case —82— as shown in Fig. 5, the gear —f— coating with the inner ends of the bearings —80— to hold the sleeve —79— against endwise movement.

It is now clear that when the motor is 25 in operation and the clutch section —89— is forced into engagement with the clutch face —87— of the crank shaft —78— reciprocatory motion will be transmitted to the plunger —29— through the medium of the pitman —76—, lever —73—, link —68— and collar —61— for operating the dashers —51— into and out of engagement with the clothes which may rest upon the perforated plate —40— near the bottom of the 35 vat.

Intermittent rotary motion.

Suitable means is provided for intermittently rotating the plunger and dashers thereon step by step in one and the same direction as the plunger is elevated, and for this purpose is provided the ratchet wheel —63— secured to the lower end of the plunger, in the manner previously described, directly above the collar —61— which has its upper end reduced in diameter to form a journal bearing for a horizontal rocking member —G— carrying a pawl —g— and a radial pin —g'—, the pawl 50 —g— being spring pressed radially into engagement with the teeth of the ratchet wheel —63— to rotate the plunger one or more tooth spaces at a time when the lever —G— is rocked in one direction and to permit said pawl to return freely across the face of the teeth.

A plate —H— is secured to the underside of the bed plate or platform —2— and extends downwardly therefrom, said plate being provided with a diagonal slot having its opposite walls forming cams —h— and —h'—, the lower end of the slot being open and disposed in the path of the vertically movable pin —g'— to receive said pin as 65 the plunger approaches the limit of its up-

ward movement and to permit it to ride against the cam face —h— for rocking the member —G— and pawl carried thereby for rotating the plunger with the dashers thereon through a limited arc as the pin 70 continues its upward movement along the cam face —h—, the opposite cam face —h'— serving to return the rocking member —G— to its starting position as the plunger is moved downwardly during which latter operation the pawl slides freely across the face of the teeth of the ratchet wheel —63—.

The lower end of the slot in the plate —H— is flared circumferentially to assure the entrance of the pin —g'— into said slot 80 when the plunger is elevated.

Wringer mechanism.

The washing machine is equipped with a suitable wringer —I— adapted to be moved 85 to and from a position across the upper end of the vat —20— and comprises a frame —i— and a pair of rollers —i'— which are adapted to be rotated in reverse directions for feeding the clothes into and out of the 90 vat.

The wringer frame —i— is provided at one end with a gear case —J— having a hub —j— mounted upon the upper end of a stationary supporting post —j'—, as shown in 95 Figs. 6 and 7, the lower end of said post being removably mounted on a tubular hub —83— of the gear case —82—.

The wringer frame is preferably made in sections, one section carrying the rollers 100 —i'— while the other section is removably mounted upon the upper end of the post —j'— by upward displacement, the sections of the wringer being secured together end to end by bolts —i'—.

The upper portion of the post —j'— just below the hub —j— may be attached to the circular band —5— or adjacent leg —3— by means of a bracket —K—, which together with the bearing at the lower end of the post 110 serves to hold it rigidly in an upright position, it being held against rotation by any suitable means, as, for example, a clamping plate —k— on the bracket —K—.

The portion of the post —j'— within the 115 hub —j— is provided with a series of, in this instance, four radial apertures —k'— arranged equal distances apart circumferentially for receiving a locking bolt —L— which is slideable radially in a socket and in one side of the hub —j— and is spring pressed 120 inwardly into the aperture —k'— which may register therewith to hold the wringer in its adjusted position, the outer end of the pawl or bolt —L— being provided with a 125 handle or knob —M— by which it may be withdrawn outwardly against the action of its retracting spring to release the wringer frame and to allow it to be turned horizontally about the axis of the post —j'— to and 130

18

on a position above one side of the tub or wringer rolls, in which case the clutch —88— would be withdrawn from engagement with its companion clutch —87—.

The supporting shaft for the lower wringer roll —i'— is extended axially and journalized in a suitable bearing —m— in the wringer frame or in one side of the gear case —J— and is provided with a gear —m'— secured thereto within said gear case.

A vertical shaft —N— extends centrally through and beyond the opposite ends of the upright posts —j'— and has its lower end journalized in a bearing 83' in the gear case —83— and its upper end journalized in bearings —n'— in the lower and upper side of the gear case —J—, the lower end of said shaft being provided with a gear —O— meshing with the gear —94— on the counter-shaft —79—.

A pair of beveled gears —o— are loosely mounted upon the upper end of the shaft —N— within the gear case —J— and are normally engaged with the lower and upper faces of the gear —n'—.

The inner ends of the beveled gears —o— are provided with clutch faces —o'— adapted to be engaged by corresponding clutch faces on the ends of an interposed clutch collar —P— which is splined upon the shaft —N— to rotate therewith and to move endwise into and out of engagement with the clutch faces —o'—.

A rock shaft —Q— is journalized in a suitable bearing —R— on the outer end of the gear case —J— and is held against endwise movement by an adjusting screw —r— which is engaged in a radial threaded aperture in the bearing —R— and enters an annular groove —r'— to hold the rock shaft —Q— is provided with an eccentric pin —S— carrying the roller —s— which rides in the annular groove in the collar —P— to adjust said collar axially into and out of engagement with one or the other of the gears —o— according to the direction in which it is desired to rotate the wringer rolls, said rock shaft being provided with a hand piece —q— by which it may be operated.

Operation.

The operation briefly described is as follows. Assuming that the motor is in operation, power may be transmitted to the plunger for reciprocating the dashers —51— vertically by simply throwing the clutch —88— to locking engagement with the companion clutch —87— by means of the hand lever —100—.

This operation may be effected without operating the wringer mechanism, which on the other hand may be operated in either direction independently of the plunger by simply shifting the clutch member —P— in one direction or the other according to the direction in which it is desired to rotate the

wringer rolls, in which case the clutch —88— would be withdrawn from engagement with its companion clutch —87—.

Or, if desired, both the plunger and the wringer mechanism may be brought into action simultaneously by the proper adjustment of both of the clutches —88— and —P—.

The operations and functions of the various other parts have been clearly defined in the foregoing description and while the construction shown is particularly simple, efficient and economical, I do not wish to limit myself to that specific construction.

What I claim is:—

1. In a mechanical clothes washing machine, a dasher and a vertically reciprocating support therefor, said dasher and support having telescoping parts to permit their relative endwise movement, and means within the telescoping parts for limiting said movement in one direction.

2. In a mechanical clothes washing machine, a dasher and a vertically reciprocating support therefor, said dasher and support having tubular telescoping parts, a coil spring extending lengthwise of and within said tubular parts and thereby protected against contact with the clothes, said spring normally exerting pressure to extend said parts, and means within the telescoping parts for limiting the extending movement of those parts.

3. In a mechanical clothes washing machine, the combination of a vertically reciprocating dasher support having a tubular hub, a bolt movable vertically through the hub, and provided with means coacting with the support for limiting its downward movement, a dasher movable vertically along the bolt and provided with a tubular hub telescoping with that of the support, said bolt having means at its lower end for limiting the downward movement of the dasher and support and a spring wholly within said hubs for normally holding said support and dasher against the limiting means, said telescoping hubs protecting the spring and bolt against contact with the clothes.

4. In a mechanical clothes washing machine, the combination of a dasher and a support therefor, said dasher and support having tubular hubs telescoping with each other for relative vertical movement, a bolt extending vertically through the telescoping hubs and provided with opposite end heads engaging the upper face of the support and lower face of the dasher, respectively, said dasher and support being movable vertically relatively to the bolt, and a coil spring within the tubular hubs and surrounding the bolt and having its ends bearing against the support and dasher to yieldingly hold the support and dasher against the heads of the bolt.

5. In a mechanical clothes washing machine, the combination of a vat, a vertically movable plunger projecting into the vat, a yoke adjustable vertically along and upon the plunger, a locking member on the yoke spring pressed into locking engagement with the plunger to hold the yoke in its adjusted position, and dashers mounted on the yoke.
- 10 6. In a mechanical clothes washing machine, the combination of a vat, a plunger projecting into the vat, a yoke mounted on the plunger and provided with upright tubular heads, dashers having hubs telescopically movable lengthwise of and within the tubular heads and free to rotate relatively thereto, and means extending through the telescoping parts of the yoke and dashers for limiting the telescoping movement of said parts.
- 15 7. In a mechanical clothes washing machine, the combination of a vat, a vertically movable plunger projecting into the vat, a yoke adjustable vertically along and upon the plunger, a locking member on the yoke spring pressed into locking engagement with the plunger to hold the yoke in its adjusted position, said yoke having a plurality of tubular heads some distance from the axis of the plunger, dashers having hubs telescoping within said heads and rotatable relatively thereto, and means for holding the hubs of the yoke and dashers in telescopic relation.
- 20 8. In a mechanical clothes washing machine, the combination of a vat, a plunger projecting into the vat, a yoke on the plunger provided with tubular hubs parallel with and some distance from the axis of the plunger, dashers having tubular hubs movable lengthwise of and within the tubular hubs of the yoke, means for holding the hubs in telescopic relation and coil springs within the hubs for extending them relatively to each other and yieldingly holding the dashers in their extended positions.
- 25 9. In a washing machine, the combination of a vat, a plunger extending through the bottom of the vat, a yoke on the plunger having a tubular head, a tubular stem telescoping with the tubular head and provided with an enlarged base, a bolt extending through the tubular head and stem and provided with adjusting nuts at both ends, a coil spring engaging opposite ends of the head and stem and surrounding said bolt, an inverted cup-shaped member seated against the lower face of the enlarged portion of the stem, a washer seated against the inner face of the cup-shaped member and engaged by the adjacent end of the bolt.
- 30 10. In a mechanical clothes washing machine, the combination of a vat having a central opening in the bottom thereof, a tubular post rigidly secured in said opening and rising some distance from the bottom, a plunger reciprocally movable vertically through the post, means for reciprocating said plunger, a yoke carried by the plunger, dashers mounted on the yoke, a gland secured to the upper end of the post around the plunger, means for intermittently rotating said plunger during its upward movement, a sleeve rotatably mounted on the post to surround the same and extending upwardly around the gland, and a movable catch on the gland for holding the sleeve against upward displacement while permitting it to rotate relatively to the post and plunger to prevent winding of the clothes around the post while the plunger and dasher-supporting yoke carried thereby are rotated.
- 35 11. In a washing machine of the character described, the combination of a frame having a substantially horizontal platform, a vat resting on said platform, a post having a reduced threaded portion extending through registering apertures in the bottom of the vat and platform, a nut engaged with the lower threaded end of the reduced portion of the post and also engaged with the underside of the platform for securing said post in place, a plunger extending through the post, a cap screwed upon the upper end of the post, around the plunger, a sleeve surrounding the post and rotatable relative thereto, a retainer ring on the cap for holding the sleeve against upward displacement, a yoke on the plunger, dashers mounted on the yoke, and means for reciprocating the plunger.
- 40 12. In a washing machine of the character described, the combination of a main supporting frame having a substantially horizontal platform, a vat having its bottom resting upon the platform, a post resting upon the bottom of the vat and rising therefrom, said post having a reduced lower end projecting through registering apertures in the bottom of the vat and platform, a nut engaged with the lower reduced end of the post and underside of the platform, a plunger extending through the post, a perforated plate around the post and covering the major portion of the bottom of the vat in spaced relation thereto, a sleeve surrounding the post and rotatable relative thereto, a yoke carried by the plunger, dashers mounted on the yoke and having the concave lower sides facing the perforated plate, and means for reciprocating the plunger.
- 45 13. In a mechanical clothes washing machine, the combination of a vat, a plunger movable vertically through the bottom of the vat, a yoke carried by the plunger, a dasher mounted on the yoke, a stationary cam beneath the vat, a ratchet wheel secured to the lower end of the plunger, a pawl-supporting member rotatably mounted on the

plunger, a pawl on said member for engaging the ratchet wheel, and means on said pawl supporting member for engaging the stationary cam as the plunger is elevated for rotating the member and pawl and thereby rotating the plunger.

14. In a washing machine of the character described, the combination of a supporting frame having a horizontal platform, a vat resting upon the platform, a cam in fixed relation to the platform, a plunger movable vertically in the vat, a yoke mounted on the plunger, dashers mounted on the yoke, a ratchet wheel secured to the plunger, a rock arm rotatable about the axis of the plunger, a pawl on the rock arm for engaging the ratchet wheel, and a pin on the rock arm movable into engagement with the cam as the plunger is moved vertically for rotating

said plunger step by step at each vertical 20 movement.

15. In a washing machine of the character described, the combination of a vat, a plunger movable vertically through the bottom of the vat, a yoke mounted on the plunger, 25 dashers carried by the yoke, means for reciprocating the plunger, a stationary cam, and means movable with the plunger and cooperating with said cam as the plunger is raised to impart rotary motion to the 30 plunger.

In witness whereof I have hereunto set my hand this 28th day of January, 1920.

JOHN NICHOLAS DERSCHUG
